UNITED STATES PATENT OFFICE.

DEAN WILLIAM CARLSON, OF MANETTE, WASHINGTON.

AUTOMATIC SWITCH.

1,391,167.

Specification of Letters Patent. Patented Sept. 20, 1921.

Application filed June 12, 1920. Serial No. 388,627.

To all whom it may concern:

Be it known that DEAN WILLIAM CARLSON, a citizen of the United States, and residing at Manette, in the county of Kitsap and 5 State of Washington, has invented certain new and useful Improvements in Automatic Switches, of which the following is a specification.

The invention relates to an improvement 10 in electrical switches of the type generally known as plug switches adapted for frictional engagement with terminals of a circuit, as in an electric iron or the like.

The present invention is directed particularly to providing a switch of this type, wherein means are arranged for automatically opening the circuit under a predetermined heat condition, in order to protect the utensil being heated. The particular 20 switch to be described and claimed is specifically constructed with a view of providing for convenient renewal of the fuse member, when replacement is required.

In the drawings:—

25 Figure 1 is a view showing the improved switch in section, and connected to the terminals of an electric iron.

Fig. 2 is a section on line 2—2 of Fig. 1.

The improved switch comprises a casing 30 1 of insulating material, formed as usual with the independent interior channels 2 and 3 communicating with an opening 4 through the end of the casing through which the conductors 5 and 6 enter the casing. 35 The opening 4 is enlarged at its inner end and provides a shoulder 7, and the usual flexible metallic cable 8 covering the wires is enlarged at 9 to fit in said enlargement 7, to thereby hold the same fixed with relation 40 to the casing at all times.

One of the conductors 5 leads to a split 45 socket 10 seated in the open end of one of the casing channels as 2, the other conductor 6 leading to a contact 11 removably secured in the other channel 3 as by a screw 12. The contact 11 has a lateral projection 13 adapted to seat in a recess 14 in the wall of the casing dividing the channels 2 and 3, to thereby hold said contact 11 with a projection 50 15 in line with the channel and presenting a square bearing face 16 transverse the channel. A socket piece 17 is arranged in the terminal of the channel 2 and is formed near one end with a lateral projection 18 adapted to seat in a recess 19 in the wall of

the channel. The socket 17 is longitudinally split at 20 for the greater portion of its length, the natural resiliency of the socket holding it locked in the channel through coöperation of the projection 18 and recess 19, the split formation permitting sufficient relative movement between the split section to disengage the lock when it is desired to move the socket.

The socket 17 terminates in a reduce member 21 in line with the member 15 of the contact 11, and interposed between these members is a fuse including a cylindrical section 22 more or less snugly fitting the channel 3 and having its end walls provided with contact terminals 23 connected by a fusible strip 24.

From the construction it is apparent that the fuse constitutes a line connection in the conductor 6, and that the fusible element will, under the predetermined degree of heat interrupt or break said connection.

When it is necessary to introduce a new fuse the old fuse and the socket member 17 may be readily removed, the new fuse inserted, and the socket member replaced. The improved switch is here shown as applied to the heating circuit terminals 25, 26 of an electric iron though it is obvious that any appropriate terminals may be engaged, 85 the sockets being interiorly formed to cooperate with the particular terminals.

Claims:

1. A plug switch including a casing having spaced terminal receiving channels, a contact member arranged in one of said channels and held against movement, a socket member removably secured in said channel, and a fuse strip arranged in said channel and bearing between the socket member and contact member.

2. A switch including a casing, a fuse carrier slidably fitted in the casing, a contact member removably secured within the casing and adapted to be engaged by the fuse carrier, and a socket member slidably mounted in the casing and formed for locking co-operation with the casing; said socket member when in locked position confining the fuse carrier between the contact member and the end of such socket member.

3. A casing divided longitudinally to form channels, a contact member removably fixed in a predetermined position in one of said channels, a socket member slidably in said

channel and formed with a projection to engage a notch in the casing wall to lock the socket member in the channel, and a fuse carrier slideable fitting in said channel and held by the socket member when in locked position to maintain electrical continuity between said contact member and socket member.

In testimony whereof I affix my signature in the presence of two witnesses.

DEAN WM. CARLSON.

Witnesses:

OSCAR HANSON,
SUZANNE McLAUGHLIN.
